United States Patent

Des. 241,915
Patented Oct. 19, 1976

241,915

BOTTLE

Paul R. Campbell and William J. O'Neil, Jr., Cincinnati, Ohio, assignors to Procter & Gamble Company, Cincinnati, Ohio

Filed May 6, 1974, Ser. No. 467,102

Term of patent 14 years

Int. Cl. D9—01

U.S. Cl. D9—59

Fig. 4

Fig. 2

Fig. 1

Fig. 3

Fig. 5

FIG. 1 is an elevational view of a bottle showing our new design, the opposite side being a mirror image of the side shown;

FIG. 2 is an elevational view looking from the left of FIG. 1;

FIG. 3 is an elevational view looking from the right of FIG. 1;

FIG. 4 is a top plan view; and

FIG. 5 is a bottom plan view thereof.

We claim:

The ornamental design for a bottle, as shown and described.
